MIXING UNIT FOR PORTABLE SANITIZING
WASHERS FOR GLASSWARE AND THE
LIKE

Matthew J. Ryan, Brookline, Mass.

Application November 13, 1950, Serial No. 195,203

3 Claims. (Cl. 299—83)

1

This invention relates to apparatus for the washing and sanitizing of equipment such as food and drink service articles including cups, glasses and other drink containers, as well as plates, dishes, implements and associated food or beverage service items. While adapted for household use the invention has reference more particularly to soda fountains, lunch counters, bars and the like. It aims to provide improved washer means of the class described and which is especially adapted to handle glassware in the use field indicated. Among the several objects is the provision of a portable, compact and relative inexpensive yet highly efficient utensil washing apparatus constructed and arranged for introduction of a detergent into the wash spray and which is well suited to the use requirements of the businesses noted including particularly the smaller establishments.

In the drawings illustrating by way of example one embodiment of the invention:

Fig. 1 is a front elevation of a complete washer unit;

Fig. 2 is a right-side elevation of the same;

Figs. 3 and 4 are respectively horizontal and vertical sections on the lines 3—3 of Fig. 1 and 4—4 of Fig. 2;

Fig. 5 is a vertical section on the line 5—5 of Fig. 2 upon a larger scale;

Fig. 6 is a partial vertical section on the line 6—6 of Fig. 1;

Fig. 7 is an enlarged vertical sectional view of one spray head or spinner; and

Fig. 8 is a further enlarged detail view as on the line 8—8 of Fig. 7 showing the spray jet orifice construction.

Referring to the drawings in further detail and first noting more particularly Figs. 1 to 4 and 6, the apparatus as here illustrated comprises a spray-tight generally cubic enclosure or cabinet 10 having top and bottom walls 11, 12, opposite side walls 13, 14, a rear wall 15 and an openable front wall 16 constituting a door adapted to be swung out and down toward the viewer in Fig. 1, by means of the handle bar or the like 16x. Such cabinet 10 may be constructed of impervious and rust-resisting sheet material, preferably a stainless steel, which or similar non-corrosive material desirably is employed for all parts subject to water and detergent contact.

In the present example the top wall 11 and the vertical end or side walls 13, 14 are formed from a single sheet, the bottom wall 12 and the back wall 15 having inturned marginal flanges as at 12x, 15x telescoped within and joined in

2

leak-proof union to the adjoined wall portions as by brazing, welding or the like. At the front the bottom wall flange 12x, see Fig. 6, provides support for the lower half of the elongated hinge means 17, see also Fig. 1, the mating upper portion of which is rigidly attached to the outer lower margin of the swinging door 16, said hinge elements being sweated, welded or otherwise securely affixed to the indicated cabinet wall portions. Coil or other spring means 17a, shown in Figs. 1 and 2 as associated with the hinge, desirably are provided, having sufficient force to urge the door to closed position, so that the door may not carelessly be left open when the spray is on, and also holding the door firmly closed during operation of the spray.

Spray shielding desirably is provided along the hinge line of the door 16. For this purpose the latter is formed with an inset and down-turned skirt 18 overlapping the hinge region and there affording direct interception of the spray fluid. Spray-proof closure likewise is provided for the other marginal portions of the door 16. As here shown, see Fig. 3, the inner side and top wall portions of the cabinet 10 around the door opening carry an inset forwardly extending continuous shielding lip 19 spaced from the adjacent wall portion sufficiently to receive with a friction fit a conforming angular flange 16a on and perpendicular to the plane of the door 16. In the closed position this door sealing flange enters between the shielding lip 19 and the cabinet wall in the manner best seen in Fig. 3, this together with the pendent door skirt 18 affording a sealing closure completely about the door 16.

The cabinet bottom wall 12 has a drainage opening 20 preferably central thereof, Figs. 3 and 4, the cabinet bottom being slightly dished toward the drain. A drain chute 21 is secured and sealed to the under-face of the cabinet bottom wall 12, extending from a position below the drain outlet 20 to one side of the cabinet, shown at the left in Figs. 1, 3 and 4. The cabinet is appropriately elevated as by angle-iron feet 22 affixed to the bottom wall 12 at the several corner regions. The cabinet is thus adapted to be removably set upon a shelf, sink drain-board or the like with the cabinet in adequately raised position to accommodate the drain chute 21 substantially as shown.

Within the cabinet the articles to be cleansed, such as the glasses g shown dotted in Fig. 4, are placed in any preferred open rack or basket such as the wire-formed cylindrical holder h also

shown dotted in Figs. 3 and 4. Such open holder for the articles, dimensioned for sidewise entry into the cabinet 10, is adapted to be supported during the washing operation in the lower portion of the cabinet 10 and spaced adequately above the bottom wall 12 to accommodate the upwardly directed rotary spray means to be described. For so supporting the article rack or holder *h* an open ledge or skeleton shelf 25 is disposed at the appropriate level above the bottom wall 12. Such rack support 25 is herein illustrated as a single rectangular frame disposed with the corners substantially central of the front, back and side walls of the cabinet where it may be fixed as by welding, brazing or the like substantially as indicated at 25x. One or more supporting legs for the shelf also may be provided, particularly adjacent the cabinet door, as at 25a, Fig. 6. The open shelf 25 and basket *h* present the articles *g* in position directly accessible to washing sprays both from below and above.

The spray-forming means comprises an up-directed lower spray element previously mentioned and preferably also a similar but inverted upper spray element directing the detergent-carrying water downwardly onto the articles. Each such spray means as illustrated comprises a rotary jet-directing element receiving rotation from the force of the fluid itself and directing a sweeping spray completely around the interior of the cabinet, in opposite rotary directions and in angularly offset relation. While in some instances a single spray head preferably below the articles may be employed, spray directed both from below and from above generally is preferable. In the latter case, and as herein illustrated, the spray elements or heads may be similarly constructed, as for example in Figs. 7 and 8. A single inlet to the cabinet for the spray water charged with detergent in a manner to be described is herein shown at about midheight of one of the vertical walls, herein the right side wall 14. Such inlet is shown as a T-coupling 30 fixed by a flange or otherwise against the inner face of the wall 14 with the single branch 31 extending out through an aperture therein. The head of the T is set vertically with the lower and upper openings coupled respectively to lower and upper L-formed feed pipes 32, 32'.

Referring now more particularly to Figs. 7 and 8 each feed pipe 32, 32' carries at the inner end, centrally of the cabinet, a bearing sleeve 33 having a lateral boss 34 bored to receive the feed pipe 32. The lower portion of the sleeve 33, as positioned in Fig. 7, is open for free entrance of the spray water and distribution thereof to the rotary sprayers. The upper portion of the sleeve 33 is reduced as at 33a to provide a cylindrical vertical bearing surface for a rotary head 35 including a tubular vertical portion 36 communicating with horizontal diametrically opposed apertures receiving the inner ends of the spray arms proper 40 fixed therein. The head 35 is formed with upper and lower horizontal surfaces 37 and 38 in the form of stepped shoulders at the upper and lower ends of the reduced portion 33a of the bearing sleeve. In the up-spraying position of Fig. 7 the rotary spray head receives horizontal bearing support mainly at said upper surface 37. Its lower reduced end is threaded to receive a retainer and bearing disc 39. In the inverted position as at the upper portion of Fig. 4 horizontal bearing support is afforded by said disc 39 and the shouldered surface 38' corresponding to surface 38 above mentioned. The receiving

chamber portion of the bearing sleeve 33 is accessibly sealed by a threaded cap 33b.

The spray members or arms 40, of which two are here shown for each head, comprise pipes or tubing of a length to extend into proximity to but with adequate clearance of the cabinet walls. Each arm 40 has a longitudinal series of jet-forming spray apertures 41. As seen for example in Fig. 3, these jet apertures 41 are arranged along a sinuous line, on each of the diametrically opposed portions of the spray arms 40, that is, at the opposite sides of the hub or rotary head 35 and 35' of the lower and the upper spray elements. Further, the sinuously disposed aperture series are differently spaced lengthwise as to the two opposed sections of each spray arm, so that the spray pattern at the opposite portions of the given arm are varied relative to each other, thus varying the spray pattern as between the two and affording greater total spray dispersion. Still further in this connection the apertures 41 are formed with vertical center lines, as seen in Fig. 8, rather than upon radial center lines. Thus additional variation of the spray pattern is had, as between apertures which are more or less spaced laterally from the central vertical plane through the arm, that is, in the direction crosswise of the sinuous curve line of the aperture series. Also for insured adequate central spray coverage jet apertures desirably are provided also in the rotary heads 35 themselves, as clearly seen in Fig. 3. As there shown these may include a central aperture and a circumferential series, the latter individually disposed with their axes at a slight angle to the vertical. As also apparent from Fig. 8 in connection with the others the location of the vertically drilled jet apertures of the sinuous series thereof includes offsetting of a number thereof to a predetermined angular extent relative to the central vertical plane. This offset angle is made sufficient so that the emergent jet affords a lateral thrust rotatively effective upon the arm and yet, largely due to the vertical axis of the individual apertures, has a main upward or downward direction permitting direct contact of the spray onto the contained articles. The preferred offset angle with respect to the vertical plane is somewhat less than 45° and of the order of 20° to 30°; Fig. 8. Noting again Fig. 7 and comparing Fig. 3 the offsetting of the jets 41 of the diametrically opposed arms of a given spray head is predominantly respectively to the opposite sides of the vertical plane. Thus at the two sides the rotating moment is effective in the same rotation-generating direction, as indicated by the arrow on Fig. 3. Also as indicated by arrows on Fig. 4, the inversion of the upper head 35' with respect to the lower head 35 causes the direction of rotational swinging of the upper and lower sprays to be mutually opposite.

As seen in Fig. 3, means desirably is included for adjusting the spray action as appropriate for the water pressure available at the particular point of use. For this purpose one or both end portions of each arm 40 have one or more jet apertures as at 41x which are adapted to be opened or closed wholly or in part by adjustable closure means shown as screw plugs 42 or caps having threaded engagement with the spray arm. By advancing these end closure members 42 into or retracting them longitudinally from the spray arm one or all of the end jets 41x may be exposed or may be covered or reduced. This serves to decrease or increase the total jet force as appropriate for the given water pressure and to regu-

late the rotational speed of the spray arms accordingly. These end jets 41x desirably also are disposed with the aperture axes inclined inwardly at an angle of about 5° to 10°, that is, with the exit ends nearer the rotary head 35 or 35' than the entrance ends at the inner face of the pipe wall. This again gives improved spray direction with reference to the side walls of the outer objects of the group thereof being treated.

The spray system coordinated with the portable enclosure or cabinet 10 further comprises in conjunction with the water inlet an injector means for introducing a detergent into the spray water. In accordance with the invention such means, while capable of handling a detergent charge in powdered form, is especially constructed and arranged to receive a pellet, wafer or like unit of the detergent material bonded together for unit handling and insertion yet readily soluble in the entering flow stream. One such pellet, which may be of any known or preferred composition having acceptable cleaning and germicidal or sterilizing properties, is indicated at P in Fig. 5.

The injector device as illustrated is carried by the external portion of the fluid inlet. As seen in Figs. 1 to 3 and on a larger scale in Fig. 5, it comprises a receiver body 50 containing a mixing chamber 51 having an inlet 52 for hot water under pressure from the supply and an outlet 53 for the detergent-charged spray fluid to the coupling branch 31 and thence to the lower and upper rotary spray heads 35. Spaced above the chamber 51 the receiver 50 has a holding cell 55 dimensioned to accept a pellet P of the calculated size and detergent content appropriate for one washing operation, and to afford flow space around the pellet. That is, the horizontal area and depth of the cell 55 are greater than the corresponding dimensions of the pellet. This space for disintegrating action of the water on the pellet is augmented by a complementary cell portion 56 in the removable top wall and closure 60 for the receiver body 50, shown as a lid or cover member conformant in size and shape to the receiver body and hinged to it as at 61. The cover cell portion 56 is circumferentially bounded by an annular rib 62 integrally formed on the under face of the cover 60 and adapted for sealing engagement in the closed cover position with a packing ring 63 of neoprene or other compressible rubberous material set into the top face of the receiver body 50 in surrounding relation to the pellet cell 55, 56.

The incoming supply water is conducted to the injector body 50 by a supply pipe or tubing 65 leading to and secured at the bottom inlet 52. It is directed to enter the pellet cell by a guiding deflector 57 centrally disposed directly opposite the inlet 52 and inclined to direct the main pressure flow to a plurality of relatively small injector ports 58 distributed circumferentially over a substantial arc of the pellet position. These injector ports admit the water at stepped-up pressure to the pellet cell 55, 56 and into dissolving contact with the pellet therein. The water and detergent charge picked up by it in the cell passes via a preferably somewhat larger cell outlet port 59, small enough to block any substantial fragments of the pellet before dissolution, to the mixing chamber 51. There it commingles with some portion of the incoming supply flow and thence through the mixing chamber outlet 53 into the described spray system for distribution to the spray heads. The cover 60 is adapted to be locked or clamped in the closed position of Figs. 1 and 2 sealing the pellet cell and

injector body as a whole. Such means is illustrated herein as a yoke 70 pivoted on one of the parts, herein the receiver body 50 as at 71 and movable into and out of a slotted lug 72 on the other part, the cover 60, and having a knurled finger-operable clamp nut 73 threaded on it for securing the yoke in locking position. Thus the injector cover 60 may readily be secured closed as in Figs. 1 and 2, or released and thrown open to receive a pellet, as in Fig. 3.

Further in accordance with the invention manual means is provided for starting and stopping a washing cycle by turning on and off the incoming hot water supply, such flow control desirably being correlated with the detergent injector means that the water may be turned on to start a cycle only when the pellet cell cover 60 is closed, thereby insuring against unintentional escape of water at the injector. Such means herein comprises an on-off and flow-regulating valve 66 installed in the supply line or pipe 65 and having an operating handle 67 of convenient size for grasping by the operator. It is arranged to have an erect position substantially as in Fig. 2 in the full off status of the valve, and to open the latter by swinging forwardly and down to the left in Fig. 2, counterclockwise. When the injector cover 60 is turned back into open or pellet-receiving position, as seen in Fig. 3, a laterally projecting lug 69 thereon stands in front of a co-operating stop lug 68 on the valve handle 67. Thus the valve is locked against opening movement unless and until the pellet-cell cover 60 is closed.

I claim:

1. For utensil washing apparatus of the cabinet type having an inlet for wash liquid, a detergent charge receiving mixing unit for mounting at the liquid inlet externally of the cabinet, said mixer being provided with a closure movable between sealing and open charge-receiving positions, a supply line to the mixer, valve means on the supply line to the mixer and having a manual operating member for starting and stopping supply of liquid to said mixer, and inter-correlating means formed by projections on the mixing unit closure and the valve operating member preventing the starting of a supply of liquid when the closure is open for insertion of a detergent charge.

2. For utensil washing apparatus having a washing compartment to receive washing liquid via an inlet, a detergent charge mixing unit for connection with the compartment inlet, comprising a mixing chamber having an inlet port for the supply liquid and an outlet port, a detergent charge holding cell communicating with the mixing chamber through a series of relatively small ports and an opposed relatively large port, and a deflector positioned at the mixing chamber inlet, whereby a substantial portion of the supply stream is diverted through the small ports to the holding cell for dissolving the detergent charge and returned through the large port to the mixing chamber for commingling with the remainder of the supply before passing from the mixer unit.

3. For utensil washing apparatus having a washing compartment to receive washing liquid supplied via an inlet, a detergent charge mixing unit for connection with the compartment inlet, comprising a mixing chamber having an inlet port for the supply liquid and an outlet port, a detergent charge holding cell communicating with the mixing chamber through a series of

relatively small ports and an opposed relatively large port, a deflector positioned at the mixing chamber inlet, whereby a substantial portion of the supply stream is diverted through the small ports to the holding cell for dissolving the detergent charge and returned through the large port to the mixing chamber for commingling with the remainder of the supply before passing to the washing compartment, a movable closure for the detergent holding cell openable for charging the same, and holding means insuring against

opening movement of the closure when supply liquid is being supplied.
